MACHINE SUCH AS A MOTOR OR PUMP FOR SERVICE WITH GASEOUS OR FLUID MEDIA, AND IN PARTICULAR A COMPRESSED AIR MOTOR

Theodor Hahn, Sprockhovel, Westphalia, Germany

Application November 2, 1954, Serial No. 466,388

Claims priority, application Germany November 6, 1953

9 Claims. (Cl. 121—48)

The present invention relates to machines such as 15 motors or pumps which are driven by, compress or deliver gaseous or fluid media, and is particularly advantageous with regard to compressed air motors.

The invention has for its object the provision of a machine for use particularly as a compressed air motor, which, while being of very simple construction, is resistant against wear and the operation of which is not affected by impurities in the driving medium. Contrary to known machines there is no difficulty in obtaining a tight seal. This results in great resistance to wear which is an extremely important factor, particularly in the case of compressed air motors which are used in underground workings.

An embodiment of the invention is illustrated by way of example in the accompanying drawing, in which:

Fig. 1 is a section taken on line 1—1 of Fig. 3 through a machine particularly suitable for use as a compressed air motor;

Fig. 2 is a section taken on line 2—2 of Fig. 3 through the same machine with the parts in different positions; and

Fig. 3 is a section taken on line 3—3 of Fig. 2 through a carrier element.

A carrier element 11 is rotatably mounted in a housing 10. The carrier element consists of a hollow cylinder carrying in its central longitudinal bore a rotary control member 12 and is enclosed in a casing 13 of yieldable, preferably rubber elastic material, as, for example, synthetic material, which is divided into three uniform sections by ribs 14 extending parallel to the longitudinal axis. The ribs 14 have thickened front portions which are received in undercut portions or reception grooves in the carrier element. Feed passages 15 and exhaust passages 16 are coordinated to each of the cells located one between each two ribs 14 and cooperate with control ports 17 and 18 in the control member 12. The feed ports 17 lead to a longitudinal bore 19 in the control member which bore, when the machine is used as a compressed air motor, is connected to the compressed air main, while the exhaust ports 18 communicate with the atmosphere through a longitudinal bore 20. Rollers 21 and 22 form supporting surfaces and are freely rotatably mounted in the housing 10 on opposite sides of the carrier element 11. The rollers may be provided with yieldable casing surfaces. Furthermore, the housing 10 also accommodates a pair of rollers 23 coordinated to the supporting rollers 21 and 22, each pair carrying an endless band 24.

The casing 13 is secured on the carrier element 11 at the sides by flange-like edge parts 25 which engage behind the undercut portions of the carrier element 11 and are held by end disks 26 fixed in position by the aid of screws 27. The carrier element 11 carries a pinion 29 keyed on a trunnion 28, which pinion transfers the output produced by the motor. When the machine is used as a pump, the pinion takes up the driving energy. Journals 30 serve for mounting the carrier element 11 in the

2

housing. However, it would likewise be possible to mount the carrier element directly on the control member 12.

For the purpose of explaining the operation of the machine it is assumed that it is to work as a compressed air motor. When the carrier element is in the position illustrated in Fig. 1 relative to the supporting rollers 21 and 22, a rib 14 forming a boundary wall of a cell has just passed the supporting roller 22 in the direction of rotation indicated by the arrow. Compressed air is now fed to the cell through the conduit 19, 17 of the control member 12 and the ports 15 in the carrier element. This inflates the portion of the cell between the rib 14 and the supporting roller 22 and produces a circumferential force driving in the direction of rotation. This drive remains effective until the ports 15 in the carrier element 11 have run over the control passages 17 of the supporting member so that the air feed is shut off (Fig. 2). The exhaust conduit 16, 18, 20 now opens either directly or after the 20 imprisoned air has expanded more or less, so that the expanded air enclosed in the cell flows off into the atmosphere. At the same time the same cycle of operations has commenced on the supporting roller 21 so that the carrier element 11 is driven more or less uniformly. The 25 endless band 24 guided over the rollers 23 limits the amount of expansion of the cell connected up with the pressure medium supply so that a good degree of efficiency is imparted to the machine.

As already mentioned the form of construction illustrated is only one possible way in which the invention can be put into effect and the invention is not restricted thereto. On the contrary many other forms of construction and applications are possible. If the machine is to be used as a pump the medium to be delivered or compressed 30 must be introduced at an initial pressure sufficient to inflate the cells. As the carrier element moves relatively to the control member the admission is closed and on the other hand the exhaust is opened. The capacity of the cell is reduced by the movement relative to the supporting 35 surface 21 or 22. Consequently the imprisoned medium is displaced and delivered or brought to a high pressure.

If the machine is employed as a motor the direction of rotation can be reversed by adjusting the control member 45 12 relatively to the position of the supporting surfaces 21, 22. There are various ways of utilizing the expansion of any kindred gaseous driving medium if the control element between the opposite ends of the longitudinal bores 19, 20 is divided and separately adjustable. The 50 constructional details of the machine can be modified in many ways. Instead of a one-piece casing the yieldable parts of the walls of the cells can also be made of separate pieces of material. When using a continuous casing, instead of the ribs, effecting the sub-division into 55 cells, spreader bars can also be provided on the outer side which are preferably embedded in the casing so that their upper surfaces do not protrude much. Furthermore, the division into cells can be attained, for example, by parts of the casing being drawn like folds into grooves 60 extending transversely to the peripheral direction by holding or stretching means.

From the above detailed description of the invention, it is believed that the construction will at once be apparent, and while there is herein shown and described a preferred embodiment of the invention, it is nevertheless to be understood that minor changes may be made therein without departing from the spirit and scope of the invention as claimed.

I claim:

1. A device of the character described comprising, in combination, a support; a rotor having a peripheral sur-

face and being rotatably mounted on said support; a first plurality of consecutive deformable wall means on said peripheral surface and forming therewith a first plurality of consecutive fluid-tight chambers; a first plurality of fluid inlet and outlet means communicating with each of said chambers, respectively; a second plurality of abutment means on said support and being arranged in the region of said peripheral wall and said deformable wall means thereon; and a second plurality of operating means, each being operatively associated with each of said fluid inlet and outlet means and with one of said abutment means in such a manner that when each deformable wall means moves past said one abutment means, fluid ingress into and fluid egress from the chamber partly formed by such deformable wall means occurs so as to deform the same and to move it into such abutting relationship with said one abutment means as to cause force-transmitting engagement between said rotor and said one abutment means in a direction corresponding to rotational movement of said rotor.

2. A device of the character described comprising, in combination, a support; a substantially cylindrical rotor having an outer peripheral surface and being rotatably mounted on said support; a first plurality of consecutive deformable wall means on said peripheral surface and forming therewith a first plurality of consecutive fluid-tight chambers; a first plurality of fluid inlet and outlet means communicating with each of said chambers, respectively; a second plurality of abutment means on said support and being arranged in the region of said peripheral wall and said deformable wall means thereon; and a second plurality of operating means, each being operatively associated with each of said fluid inlet and outlet means and with one of said abutment means in such a manner that when each deformable wall means moves past said one abutment means, fluid ingress into and fluid egress from the chamber partly formed by such deformable wall means occurs so as to deform the same and to move it into such abutting relationship with said one abutment means as to cause force-transmitting engagement between said rotor and said one abutment means in a direction corresponding to rotational movement of said rotor.

3. A device of the character described comprising, in combination, a support; a substantially cylindrical hollow rotor having an inner peripheral surface and being rotatably mounted on said support; a first plurality of consecutive deformable wall means on said peripheral surface and forming therewith a first plurality of consecutive fluid-tight chambers; a first plurality of fluid inlet and outlet means communicating with each of said chambers, respectively; a second plurality of abutment means on said support and being arranged in the region of said peripheral wall and said deformable wall means thereon; and a second plurality of operating means, each being operatively associated with each of said fluid inlet and outlet means and with one of said abutment means in such a manner that when each deformable wall means moves past said one abutment means, fluid ingress into and fluid egress from the chamber partly formed by such deformable wall means occurs so as to deform the same and to move it into such abutting relationship with said one abutment means as to cause force-transmitting engagement between said rotor and said one abutment means in a direction corresponding to rotational movement of said rotor.

4. A device of the character described comprising, in combination, a support; a rotor having a peripheral surface and being rotatably mounted on said support; a first plurality of consecutive deformable wall means on said peripheral surface and forming therewith a first plurality of inflatable and deflatable consecutive fluid-tight chambers; a first plurality of fluid inlet and outlet means communicating with each of said chambers, respectively; a second plurality of abutment means on said support and being arranged in the region of said peripheral wall and

said deformable wall means thereon, each of said abutment means including a pair of abutment members one of which is near said peripheral surface and said deformable wall means thereon while the chamber partly formed thereby is deflated and the other of which is radially spaced from said peripheral surface; and a second plurality of operating means, each being operatively associated with each of said fluid inlet and outlet means and with one of said abutment means in such a manner that when each deformable wall means moves past said one abutment means, fluid ingress into and fluid egress from the chamber partly formed by such deformable wall means occurs so as to inflate the chamber and to move such deformable wall means into such abutting relationship with said abutment members of said one abutment means as to cause force-transmitting engagement between said rotor and said one abutment member of said one abutment means in a direction corresponding to rotational movement of said rotor.

20 5. A device as defined in claim 4 wherein said other member of each of said abutment means includes a pair of roller members and an endless band carried thereby, said roller members being so arranged that a portion of said band is coextensive with a portion of said peripheral surface of said rotor and said deformable wall means thereon and is spaced therefrom while said chambers are deflated, said portion of said band being adapted to be engaged by said deformable wall means when the chamber partly constituted thereby is inflated, thereby limiting the radial expansion thereof.

6. A device as defined in claim 1 wherein said deformable wall means are constituted by a sheet of deformable material encompassing said rotor, said sheet being fluid-tightly connected to said peripheral surface of said rotor along a first plurality of longitudinal portions so as to form said first plurality of consecutive fluid-tight chambers.

35 7. A device as defined in claim 6 wherein said rotor is formed with a first plurality of longitudinal recesses and wherein said first plurality of longitudinal portions of said sheet are respectively constituted by a first plurality of longitudinal ribs respectively arranged within said longitudinal recesses.

8. In a machine such as motor or pump for service with gaseous or fluid media, in which a pressure chamber is partly closed by a movable wall which can be pressed by means of a supporting surface against a solid wall, in particular a compressed air motor, spaced supporting surfaces, a carrier element rotatable relatively to and between said supporting surfaces, cells distributed around the periphery of the carrier element and being formed by the wall of the carrier element on the one hand and by a casing of yieldable material surrounding the carrier element on the other hand, said casing being firmly connected to the carrier element by ribs extending transversely to the circumferential direction and being distributed around the periphery at distances apart, said casing constituting movable wall parts partly closing said cells, an inlet port and an outlet port in each of the cells, and a controlling device for the inlet and outlet ports, rotatable relatively to the carrier element.

9. In a machine such as motor or pump for service with gaseous or fluid media, in which a pressure chamber is partly closed by a movable wall which can be pressed by means of a supporting surface against a solid wall, in particular a compressed air motor, spaced supporting surfaces, a carrier element formed with undercut portions of grooves and being rotatable relatively to and between said supporting surfaces, inflatable cells distributed around the periphery of the carrier element and being formed by the wall of the carrier element on the one hand and by a casing of yieldable material surrounding the carrier element on the other hand, said casing being firmly connected to the carrier element by ribs extending transversely to the circumferential direction and

engaging behind said undercut portions of grooves in said carrier element, said casing constituting movable wall parts partly closing said cells, an inlet port and an outlet port in each of the cells, and a controlling device for the inlet and outlet ports, rotatable relatively to the carrier element. 5
